I. BREWSTER.
CHURN.

Patented Dec. 31, 1833.

Dec 1

Dec 31, 1833 249.

John Brewster Plattsburgh N.Y. 7919X
S. Morris M'Inty

The object of the referred to in these Letters Patent are making part of the same
containing a description in the words of the said John Brewster himself of his
invention in the China

To all whom these presents shall come: .....

Be it known that I John Brewster of,
Plattsburgh in the County of Clinton and State of New York have invented a new
and useful improvement in the China and that the following is a full and
exact description of the construction and operation of the same machine as
invented and improved by me viz: .....

A common round China body is fastened
to the top of which is a square iron frame two feet four inches long
and two inches wide. Since the diameter of the China top the lower top piece
of the frame to be three inches above the top of the China. A four 1/2 inch
bent at right angles with a sharp point two inches placed near the top of
the frame and two within it by means of a brack on the outside of
the frame to each of the four angles of the brack within the frame is fastened
a pointed sixteen inches long the lower ends of which are also fastened
against to shafts or clamps which pass through the lower top piece of frame
and out of the China and may be moved as you please. By turning the brack
the shafts or clamps are fast in constant alternate motion. ....

In witness whereof I have hereunto subscribed my
name this 17 day of December 1833

John Brewster
